LEWIS G. CARR, OF PHILADELPHIA, PENNSYLVANIA, ASSIGNOR
TO HIMSELF AND A. M. WALKER, OF SAME PLACE.

Letters Patent No. 91,713, dated June 22, 1869.

PIPE AND TOBACCO-BOX.

The Schedule referred to in these Letters Patent and making part of the same.

To all whom it may concern:

Be it known that I, LEWIS G. CARR, of Philadelphia, Pennsylvania, have invented an Improved Tobacco-Box; and I do hereby declare the following to be a full, clear, and exact description of the same.

My invention consists of a tobacco-box, having a hinged lid, in which is formed a receptacle for matches, as fully described hereafter, the box being of such a size and form that it can be conveniently carried in the pocket.

In order to enable others to make and use my invention, I will now proceed to describe the mode of constructing and using the same, reference being had to the accompanying drawing, which forms a part of this specification, and in which—

Figure 1 is a vertical section of my improved tobacco-box, and

Figure 2, a perspective view of the same with the lid opened.

The body A of the box is divided by a partition, a, into two compartments, b and b', the former of which is so shaped as to receive a pipe, c, the latter being a receptacle for smoking-tobacco.

The partition a is so arranged within the box that the lower end of the compartment b, into which the stem of the pipe is inserted, shall be considerably decreased in width, and the capacity of the compartment b', for the tobacco, correspondingly increased.

In order to prevent the tobacco from escaping from the compartment b' into the other portions of the box,

the said compartment is provided at the top with a movable lid, f.

The hinged lid B of the box is of sufficient depth to contain a quantity of matches, which are prevented from falling from the lid, when the box is opened, by a plate, h, hinged at one end to the lid, and connected to the latter at the opposite end by a spring-catch, i.

This plate h is serrated or roughened, as best observed in fig. 2, so that matches can be ignited by being drawn across it; and a slot, j, at the outer end of the plate, permits the latter to be readily thrown back by the lid, when it is desired to obtain access to the matches.

It is not essential, in carrying out my invention, that the body of the box should be divided into two compartments, as in some cases it may be desired to carry the pipe separately.

I therefore claim as my invention, and desire to secure by Letters Patent—

1. The box A, with its lid B, covering a compartment b, open at the top, and compartment b', provided with a lid, f, all as set forth.

2. The arrangement of the hinged serrated plate h, in the lid of the box, as described.

In testimony whereof, I have signed my name to this specification, in the presence of two subscribing witnesses.

Witnesses:

LEWIS G. CARR.
